UNITED STATES PATENT OFFICE

135,081

DESIGN FOR A VISE

Wallace E. Breuner, Oakland, Calif.

Application September 29, 1942, Serial No. 108,359

Term of patent 3½ years

To all whom it may concern:

Be it known that I, Wallace E. Breuner, an employee of the United States Government, a citizen of the United States, residing at Oakland, California, have invented a new, original, and ornamental Design for a Vise of which the following is a specification, reference being had to the accompanying drawing, forming part thereof.

Fig. 1 is a plan view of a vise, showing my new design,

Fig. 2 is a side elevational view thereof,
Fig. 3 is an end elevational view of the left end, and

Fig. 4 is an end elevational view of the right end.

I claim:

The ornamental design for a vise, as shown.

WALLACE E. BREUNER.
